UNITED STATES PATENT OFFICE.

CHARLES BENJAMIN REDRUP, OF CANTON, CARDIFF, ENGLAND.

REVOLVING-CYLINDER INTERNAL-COMBUSTION ENGINE.

Specification of Letters Patent. Patented Dec. 17, 1912.

1,047,839.

Application filed June 15, 1911. Serial No. 633,337.

To all whom it may concern:

Be it known that I, CHARLES BENJAMIN REDRUP, a subject of the King of England, residing at Canton, Cardiff, county of Glamorgan, England, have invented certain new and useful Improvements in Revolving-Cylinder Internal-Combustion Engines, of which the following is a specification.

This invention is for improvements in or relating to internal combustion engines of the type wherein the cylinders are disposed radially to the crank-shaft and rotate relatively thereto and preferably the crank-shaft also rotates in the reverse direction to the cylinders.

Another feature of this invention consists in the employment of a drum-shaped crank-chamber that has cylinders arranged radially around the cylindrical portion of the crank case, every alternate cylinder being staggered so that a space is left between any first and third cylinder to accommodate induction pipes, tappet rods, and associated parts.

The invention further relates to constructional details of the rotating crank-case and associated parts, the novel features of which details are set forth in the claims.

In the accompanying drawing the cylinders A are radially disposed around the periphery of a drum-shaped crank-chamber B and alternate cylinders are staggered so that a space B¹ is left between the first and third cylinders a, a' on the left of the figure, and a space B² is left between the first and third cylinders a², a³ on the right of the figure. In the space B¹ the two induction pipes C, C¹ of two adjacent cylinders are accommodated and in the space B² the valve-operating mechanisms D, D¹ of two adjacent cylinders are accommodated. From the above description it will be seen that half of the cylinders lie in one plane and the other half in another plane, those in one plane being situated opposite the spaces between those in the other plane.

The crank-chamber B has one end wall hollow so that a chamber B³ is formed within the wall and communication is made between this and the induction pipes of the cylinders, by a hollow channel in part of the circumferential wall. The end wall referred to carries a hollow trunnion E and surrounding this is a hollow ring F. The ring F is stationary and constitutes an annular chamber which communicates with a

carbureter F¹. The ring F has ports F² formed in it on that side which is toward the end wall of the crank-chamber and the crank-chamber has in this wall corresponding ports B⁴. The ring F is maintained against the wall of the crank-chamber by a spring or other means not shown and the explosive fluid passes readily from it to the chamber B³ in the wall of the crank-case by the ports F² and B⁴. On the other side of the crank-case B the end wall B⁵ has a hollow trunnion E¹ and within the trunnions E, E¹ though not necessarily in direct contact therewith, lies the crank-shaft G.

The crank-case is supported on the left-hand side of the figure by a ball-bearing H through the cupped end J¹ of a shaft J is introduced between this bearing and the trunnion E which extends beyond the bearing and is made a tight fit within the cupped end J¹. The other side of the crank-case B is adapted to be supported in a similar manner.

The hollow end wall of the left-hand portion of the crank-case as shown in the drawing, is conveniently cast in one with the cylinder carrying portion.

The cup-shaped end J¹ of the shaft J is provided with a lubricating conduit L⁶ and ring L⁷, the end of the shaft G being bored at G⁸ to conduct the lubricant to the crank nearest that end of the shaft. It will be noted, of course, that the opposite end of the shaft G is adapted to be lubricated in a similar manner.

It will be understood that the ball-bearings H, referred to as carrying the crank-case by means of the parts connected therewith, are themselves carried by any suitable stationary support which it is not necessary to show in the drawing.

An important feature in the construction of this engine is that the arrangement of the parts described above enables the valve mechanism and the magneto mechanism each to be operated in proper time relation to the relative rotation of the crank shaft and cylinder without interposition of any fixed member, that is to say that all the gear which effects the proper relative movement of these parts is carried by the moving parts of the engine; thus the whole engine and gear can be removed bodily out from its bearings and replaced therein without any derangement of the timing of the various elements. This arrangement more-

over permits the shaft and cylinder members to rotate either at the same or different speeds according to their load and one of these elements can even be held stationary 5 without interfering with the proper operation of the engine.

- It will be appreciated that the hollow end wall in the crank-chamber and the hollow channel in the circumferential wall of the 10 same is a convenient method of conveying the explosive fluid from the ring F to the induction pipes. A drum-shaped crank chamber having a hollow end wall however, is not new in itself.
- 15 5. What I claim as my invention and desire to secure by Letters Patent is:—
1. In an internal combustion engine, the combination of a casing; a plurality of cylinders mounted on and disposed radially of 20 the casing, said cylinders arranged in staggered relation to provide spaces between alternate cylinders; and fuel feeding, and controlling means therefor mounted within said spaces, substantially as described.
  2. In an internal combustion engine, the combination of a casing; a plurality of cylinders mounted on and disposed radially of 25 the casing, said cylinders arranged in staggered relation to provide spaces between alternate cylinders; and fuel induction pipes for said cylinders mounted within said spaces, substantially as described.
  3. In an internal combustion engine, the combination of a casing; a plurality of cylinders mounted on and disposed radially of 30 the casing, said cylinders arranged in staggered relation to provide spaces between alternate cylinders; and valve actuating mechanism for said cylinders mounted within 35 said spaces, substantially as described.
  4. In an internal combustion engine, the combination of a casing; a plurality of cylinders mounted on and disposed radially of 40 the casing, said cylinders arranged in staggered relation to provide spaces between alternate cylinders; valves on said cylinders; and valve actuating tappet rods mounted to operate within said spaces, substantially as described.
  5. In an internal combustion engine, the

combination of a casing; a plurality of cylinders mounted on and disposed radially of the casing, said cylinders arranged in staggered relation to provide spaces between alternate cylinders; and said spaces disposed alternately to either side of the casing; fuel induction pipes for said cylinders mounted within said spaces to one side of the casing; and valve actuating mechanism for said cylinders mounted within the spaces on the other side of said casing, substantially as described. 55

6. In an internal combustion engine, the combination of a casing; a plurality of cylinders mounted on and disposed radially of 60 the casing, said cylinders arranged in staggered relation to provide spaces between alternate cylinders; and fuel induction pipes for an adjacent pair of said cylinders mounted within one of said spaces, substantially as described. 70

7. In an internal combustion engine, the combination of a casing; a plurality of cylinders mounted on and disposed radially of 75 the casing, said cylinders arranged in staggered relation to provide spaces between alternate cylinders; and fuel induction pipes for each adjacent pair of cylinders mounted with each of said spaces on one side of the casing, substantially as described. 80

8. In an internal combustion engine, the combination of a casing; a plurality of cylinders mounted on and disposed radially of 85 the casing, said cylinders arranged in staggered relation to provide spaces between alternate cylinders; fuel induction pipes for each adjacent pair of cylinders mounted within each of said spaces on one side of the casing; and valve actuating mechanism for each adjacent pair of cylinders mounted 90 within each of said spaces on the other side of the casing, substantially as described. 90

In testimony whereof I have signed my name to this specification in the presence of two subscribing witnesses.

CHARLES BENJAMIN REDRUP.
